CHIMNEY, DUCT, AND THE LIKE

Albert Victor Staniforth, Withernsea, England

Application August 12, 1941, Serial No. 406,562

In Great Britain February 2, 1940

11 Claims. (Cl. 72—94)

The present invention relates to chimneys, flues and the like, and to ducts such as are used in boiler installations and is particularly concerned with steel chimneys. For many purposes such chimneys must be lined with a protective coating, various types of which have been proposed and used in practice.

One of the most satisfactory types of lining is pre-formed from a moulded plastic material, in the form of panels which are fixed in the chimney. Difficulty is met with however in the fixing of such lining panels since these must be firmly fixed and furthermore the whole of the joints between adjacent panels must be covered to prevent gases and moisture from reaching the steel chimney plates and leading to corrosion.

Heretofore it has been the usual practice to use a broad metal strip which both covers the joints between the panels and also secures the latter to the steel plates of the chimney, studs or bolts being located at suitable intervals for this purpose.

Such cover strips have to withstand corrosion and erosion due to the moisture, acids and varying temperatures of the flue gases and furthermore must have a certain amount of flexibility. All these properties are not found in the relatively inexpensive materials and it would be necessary to employ relatively expensive resistant alloys, which unduly increases the cost of the lining. One of the most satisfactory materials would be cast iron since it is cheap and is resistant to corrosive and erosive action but it could not be used heretofore owing to its low tensile strength, and cover strips formed therefrom would become broken and useless due to expansion and contraction and to wind sway.

The principal object of the present invention is to provide an improved method of and means for securing pre-formed lining panels of a chimney or the like employing cast iron cover strip; the construction allowing for a slight degree of movement without distorting the cover strips.

In accordance with the present invention a chimney, or the like is provided with a lining in the form of separate panels and said panels are secured to the chimney or like wall by means of clamps located at successive points and cover strips or bars which are engaged by said clamps to hold the panels in position and to cover the joints between adjacent panels.

Preferably the said clamps are also formed of cast iron and are located at the points where several panels meet. They are provided with arms or lugs on two, three or four sides accord-

ing to the number of cover strips converging on or running to said clamps. The ends of the cover strips are reduced in thickness to engage under the arms or lugs of the clamps.

One preferred construction is illustrated on the accompanying drawing in which:

Fig. 1 is a fragmentary elevational view of the lining assembly,

Fig. 2 is a sectional view of a fixing clamp, the end portion of a cover bar being indicated in dotted lines,

Fig. 3 is a plan of the clamp,

Fig. 4 is an end elevation of a cover bar,

Figs. 5 and 6 show in elevation two forms of cover bar, and

Fig. 7 is a fragmentary sectional elevational view illustrating the application of the invention to a typical chimney or stack.

As shown in Fig. 1 a preferred lining for a chimney or the like according to the present invention, comprises a plurality of lining plates 1 of a suitable moulded or pressed plastic resistant material, held in position by cover bars 2 secured by clamps 3 fixed to the chimney wall 12 by means of tap bolts or other suitable fastening means.

As shown in Figs. 2 and 3 the clamps 3 are formed of cast iron and are broadly of square shape with a recess 4 in the upper face to take the head 5 of a tap bolt or the like which serves to secure the clamp to the steel plates of the chimney. The clamps 3 are provided with lugs 6 on two or more sides. These lugs are disposed in pairs, leaving a gap 7 between them to engage a rib, referred to hereinafter, on the cover bars. The lugs 6 are so spaced from the base of the clamp that the cover strips or bars 2 are forced tightly against the lining panels as indicated on Fig. 2.

The cover strips or bars 2 are formed of cast iron and are shown more clearly in Figs. 4 to 6. They may be of various sections, for example arcuate or chord shaped or they may be of inverted V or channel section. If desired transverse webs 8 may be provided in the concave part of said cover strips to give additional strength, said webs extending to near the lateral edges of the cover strips. At each end said cover strips are cut away or recessed to form a step 9 which is adapted to engage under the lugs 6 on the clamps. Preferably an upwardly directed rib or fin 10 is formed on said step, which rib is adapted to fit in the gap 7 between the pairs of lugs 6 on the sides of the clamps and thus prevent lateral displacement of the cover strips,

The part of said step engaged by the lugs is preferably enlarged or thickened on the upper face as shown at 11.

In the formation of a chimney lining in accordance with the present invention, the clamps 3 are located at the points where several panels 1 join; clamps having two or more sets of lugs being used according to whether there are two or more lines of joint to be covered. In the position indicated in Figs. 1 and 7, it is assumed that the clamp 3 is located at a point where four panels join, and such clamp is provided with lugs 6 on all four sides. Of course some of the joints may extend peripherally of the chimney and in such case the cover strips concerned would be curved to suit the configuration of the chimney as indicated on Fig. 6, while other lines of joint might extend vertically and straight cover strips, as shown in Fig. 5, would be used. Also if lengthy lining panels were used, one or more clamps could be disposed intermediately of a single line of joint, such clamps having lugs on two opposite sides only.

The lining plates may be bedded on a plastic coating layer and the cavity under the cover strips is also filled during assembly with a plastic filling compound to ensure complete sealing of the joints, while furthermore the recess 4 is filled with a plastic compound so that the head 5 of the bolt is protected.

It will be appreciated that the method described ensures a secure fixing of the lining panels and an efficient sealing of the joints but the expansion and contraction of the chimney does not lead to detrimental stressing of the clamps or cover strips owing to the articulated or semi-free connection between these parts which allows a limited degree of free movement.

I claim:

1. A chimney, duct or the like comprising an outer structure forming the chimney proper, a plurality of lining panels within said structure, cast iron cover bars covering the joints between adjacent panels, clamps engaging said cover bars and means to secure said clamps to the aforesaid structure.

2. A chimney, duct or the like comprising a steel outer body, a plurality of resistant lining panels within said body, cast iron cover bars covering the joints between adjacent panels, clamps engaging the ends of said cover bars and means to secure said clamps to the aforesaid outer body.

3. A chimney, duct or the like comprising an outer structure forming the chimney proper, a plurality of resistant lining panels within said structure, cast iron cover bars covering the joints between adjacent panels and holding the latter in position within the outer structure, clamps positioned adjacent the ends of a plurality of said cover bars, means on said clamps to engage the ends of said cover bars and means to secure said clamps to the said outer structure.

4. A chimney, duct or the like comprising an outer structure forming the chimney proper, a plurality of resistant lining panels within said structure, cast iron cover bars to cover the joints between adjacent panels and to hold the latter in position, said bars being cut away at the ends to form a step, clamps positioned adjacent the ends of a plurality of cover bars, lugs on said clamps to engage the steps formed on the ends of the cover bars and to force the latter against the lining panels to hold the said panels in position and means to secure said clamps to the aforesaid outer structure.

5. A chimney, duct or the like comprising an outer structure forming the chimney proper, a plurality of resistant lining panels within said structure, cast iron cover bars to cover the joints between adjacent panels and to hold the latter in position, said bars being cut away at the ends to form a step, an upstanding rib midway of said step, clamps positioned adjacent the ends of a plurality of cover bars, lugs on said clamps to engage the steps formed on the ends of the cover bars, said lugs being disposed in pairs to leave a gap engageable by the aforesaid rib and means to secure said clamps to the aforesaid outer structure.

6. A chimney, duct or the like comprising an outer structure forming the chimney proper, a plurality of resistant lining panels within said structure, cast iron cover bars to cover the joints between adjacent panels and to hold the latter in position, said bars being of arcuate section and being cut away at each end to form a step, strengthening ribs within the arcuate parts of said bars, clamps positioned adjacent the ends of a plurality of cover bars, lugs on said clamps to engage the steps formed on the ends of the cover bars and to force the latter against the lining panels to hold the said panels in position, and means to secure said clamps to the aforesaid outer structure.

7. A chimney, duct or the like comprising an outer structure forming the chimney proper, a plurality of resistant lining panels within said structure, cast iron cover bars to cover the joints between adjacent panels and to hold the latter in position, clamps positioned adjacent the ends of a plurality of cover bars and adapted to engage the ends of said bars, said clamps being provided with a recess and means to secure said clamps to the aforesaid outer structure said fixing means being located within said recess and recess being filled with a plastic resistant compound.

8. A chimney, duct or the like comprising an outer structure forming the chimney proper, a plurality of resistant lining panels bedded on a plastic resistant coating layer within said outer structure, cast iron bars covering the joints between adjacent lining panels, the cavities under said bars being filled with a plastic resistant coating layer, clamps engaging the ends of said cover bars and means to secure said clamps to the aforesaid structure.

9. A chimney, duct or the like comprising an outer structure forming the chimney proper, a plurality of lining panels within said outer structure, cast iron cover bars covering the joints between adjacent lining panels, square shaped clamps positioned to come where the corners of several lining panels are located, lugs on some of the sides of said clamps to engage the ends of the cover bars and means to secure said clamps to the aforesaid structure.

10. A chimney, duct or the like comprising an outer structure forming the chimney proper, a plurality of curved lining panels within said outer structure, cast iron cover bars, some of which are curved and extend peripherally and others are straight and extend lengthwise to cover the joints between adjacent lining panels, clamps positioned to come where the corners of several lining panels abut and adapted to engage the ends of the cover bars and means to secure said clamps to the aforesaid structure.

11. A chimney, duct or the like comprising an outer structure forming the chimney proper, a

plurality of curved lining panels within said outer structure, cast iron cover bars formed to cover the joints between adjacent lining panels, said panels and said bars being bedded on a plastic resistant coating layer, said bars being formed with a reduced step at each end, an upstanding rib associated with said step, clamps positioned at the points where the corners of several lining panels abut, pairs of lugs on the sides of said

5 clamps to engage the ends of said bars, said upstanding rib being positioned between the pairs of lugs and said clamp being provided with a deep recess, a bolt for securing each clamp to the said structure the head thereof being located in said recess and a plastic resistant filling in said recess around the head of said bolt.

ALBERT VICTOR STANIFORTH.
